(57) **CLAIM**

The ornamental design for an adjustable golf tee assembly, as shown and described.

DESCRIPTION

FIG. 1 is a front perspective view of an adjustable golf tee assembly showing my new design;

FIG. 2 is a front elevation view, the sides and rear views being identical thereof;

FIG. 3 is a top plan view thereof;

FIG. 4 is a bottom plan view thereof;

FIG. 5 is a front perspective of the adjustable golf tee assembly of FIG. 1, showing the tee in an extended configuration; and,

FIG. 6 is a front view of FIG. 5, the sides and rear view being identical thereof.

The broken lines in the drawings depict portions of the adjustable golf tee assembly that form no part of the claimed design.

1 Claim, 5 Drawing Sheets
